Bartlesville, Okla. 74003
Filed June 16, 1965, Ser. No. 464,450
10 Claims. (Cl. 222—57)

This invention relates to an apparatus and method for dispensing and mixing a solid with a liquid and particularly to an apparatus and method for accurately dispensing and homogeneously mixing dry, particulate material with a liquid.

Heretofore is has been known to mix a solid such as a dry chemical with a liquid or solvent to provide a liquid mixture which, in turn, was further mixed with a liquid primary system. However, certain disadvantages are associated with prior art methods such as inaccuracies in measuring an exact predetermined amount of dry chemical, cumbersome and time-consuming efforts in delivering an exact predetermined amount of the dry material to a mixing zone as well as efficiently and simply producing a homogeneous liquid mixture. Further conventional safety measures, often difficult to control or monitor, were required to insure against discharge or loss of the dry chemical in the event of shut-down of associated equipment, interruption of liquid flow to the mixing vessel or malfunction of the primary system to which the liquid mixture was delivered.

It is therefore a principal object of the instant invention to provide a machine and a method adapted to initially dispense and mix materials of the type referred to whereby a substantially homogeneous liquid mixture is produced and to subsequently feed the mixture under controlled conditions to a liquid primary system.

It is a further object of the instant invention to provide an apparatus adapted to automatically and efficiently dispense and mix a predetermined amount of a dry, particulate material with a liquid to provide a liquid mixture of the material.

Still a further object of the instant invention is to provide an apparatus adapted to automatically dispense said liquid mixture into a liquid primary system.

Another object of the instant invention is to provide an improved method for accurately dispensing and mixing a dry, particulate material in a liquid to provide a substantially homogeneous liquid mixture and to deliver said mixture to a liquid, primary system.

Still another object of the instant invention is the provision of a novel method and apparatus for preparing and dispensing an aqueous mixture of a dry chemical such as sodium tripoly phosphate used as an aid in stimulating oil recovery by water flooding techniques.

Other objects will be in part obvious, and in part pointed out hereinafter.

The invention and the novel features thereof may best be made clear from the following description and the accompanying drawings, in which:

FIGURE 1 is a diagrammatic view of an exemplary apparatus embodying the principles of the instant invention;

FIGURE 2 is a fragmentary view, taken substantially along the line 2—2 of FIGURE 1, showing a mechanism for dispensing predetermined amounts of a dry, particulate substance;

FIGURE 3 is a sectional view taken substantially along the line 3—3 of FIGURE 2;

FIGURE 4 is an exploded perspective view of a dispensing mechanism suitable for use in the instant invention;

FIGURE 5 is a perspective view of another embodiment.

2

ment of the dispensing mechanism suitable for use with the instant invention; and

FIGURE 6 is a circuit diagram of the electrical control system of the apparatus of the invention.

Referring to the drawings, particularly FIGURE 1, the exemplary embodiment of this invention comprises a frame or platform 10 which supports a mixing vessel 12 into which is introduced a liquid and predetermined amounts of a dry, particulate material. The vessel 12 is, preferably, rectangular in shape having a closed bottom 14, an open top 16, front and rear walls 18, and side walls 20.

Mounted longitudinally over the open top 16 is dispensing mechanism 22 which is fixedly attached and supported by front and rear brackets 24. The brackets 24 are secured to the vessel 12 by plate 26 longitudinally disposed above the open top 16 of the vessel and secured thereto in any convenient manner such as by bolts 28. The plate 26 extends from the rearward edge 30 of the vessel's open top and extends forwardly adjacent the forward edge 32 and spacedly removed therefrom to provide an aperture 34 thus exposing the contents of the vessel 12 to the atmosphere. The plate 26 is provided with a longitudinally extending aperture 36 for communication between the dispensing mechanism 22 and the interior of the mixing vessel 12.

The dispensing mechanism 22, in one embodiment, comprises a cylinder 38 having a longitudinally extending aperture 40 for introducing the dry, particulate material therein. The cylinder 38 is closed at both ends by circular plates 42 extending radially outwardly from the cylinder. The cylinder 38 is journalled between spacedly removed vertical plates 44 and 46 on shaft 48 provided with bearings 50 and 52. The bearings 50 and 52 are supported by brackets 54 and 56 fixedly attached to side plates 44 and 46, respectively, which, in turn, are attached to the plate 26 by brackets 58 and 60 by any conventional means such as by welding.

Symmetrically and longitudinally disposed about the cylinder 38 and spaced therefrom are front and rear arcuate shroud members 62 and 64 provided adjacent their outer ends with a radially extending flange member 66. The shroud members are held in place by removably fastening the flange members to the vertical plates 44 and 46 in a convenient manner.

Adjacent the upper portion of the cylinder at its outer ends are a pair of downwardly extending end shroud members 68 removably attached to the vertically depending legs 70 of the downwardly inclined front and rear baffle plates 72 of the hopper 74.

The hopper 74 is provided with an open bottom 76 which is in communication with the aperture 40 of the cylinder 38 through the front and rear baffle plates 72. A dry, particulate material is conveniently stored in the hopper 74. The hopper 74 can be provided with a removable top closure member 78.

Operatively connected to the shaft 48 of the dispensing mechanism 22 is actuating means 80, preferably a reversible electric motor, the actuation of which can be controlled by electrical control system 82. Also controlled by the electrical control system 82 is liquid level sensing means 84 which controls the operation of pump means 86, the inlet end 88 of which is in communication with a source of liquid (not shown) which liquid is to be employed for mixing the dry, particulate material in vessel 12. The outlet end 90 of pump means 86 is in fluid communication with inlet 92 of filter means 94 through conduit 96. Filter means 94 serves to remove substantially any extraneous material from the liquid, thus assuring an essentially pure, homogeneous liquid mixture since extraneous materials in the liquid, unless removed, often disadvantageously react with the dry, particulate

material to seriously interfere with the results desired. The outlet end 98 of filter means 94 is in fluid communication with solenoid valve 100, through conduit 102. The solenoid valve 100, in turn, is in operative communication with liquid flow sensing means comprising flow valve 104, which is electrically controlled by system 82. Conventional liquid flow sensing means are disclosed, for instance, in U.S. Patents 1,952,397; 2,638,582; 2,768,369; 3,095,902; 3,091,758; 3,057,977; 2,966,133; 2,772,409; 2,769,121 and 2,677,023. The outlet 106 of flow valve 104 is in fluid communication with the inlet of conduit 108 leading to the interior of vessel 12. The outlet of conduit 108 is, preferably, fitted with a nozzle 110 for effecting a mixing action in the liquid pumped into the vessel, thus assuring a substantially homogeneous liquid mixture of the dry, particulate material.

In fluid communication with the vessel 12 is an outlet 112 adjacent the bottom thereof but below the low liquid level sensing device provided therein. Outlet 112 is in fluid communication with the intake end 116 of pump means 114 through conduit 118. The discharge end 120 of pump means 114 is in fluid communication with a fluid primary system through proportioning conduits 122 and 124.

An alternative dispensing mechanism useful in the instant invention is shown in FIGURE 5 and comprises a cylinder 126 provided with a plurality of apertures 128 in staggered relationship with each other about the periphery thereof. The position of the apertures can be predetermined so that on rotation of the dispensing mechanism the contents thereof will be sequentially introduced into the vessel 12 at predetermined time intervals. Between immediately adjacent apertures 128, there is provided a circular spacer element 130 fixedly and centrally attached to the shaft 48, the periphery of each spacer element 130 is in sealing engagement with the inside wall of the cylinder 126.

The electrical control system of the dispensing and mixing device of this invention is designed to properly coordinate the various operations of the device and maintain continuous operation. The system, shown in FIGURE 6, will now be described in detail.

The control system is powered conveniently by a source of 110 volt alternating current supplied through a main switch (not shown) located desirably at the main control station of the device. The switches and contacts in the circuit diagram illustrated are in their respective positions when the water in the vessel 12 just reaches its highest predetermined level. Thus contact C₁ closes and the current flows through conductors 132, 134, 136, 140, relay R₁, and conductors 142 and 144. On energization of relay R₁, contacts C₂, C₃, and C₄ close and current flows through conductors 132, 134, 136, 146, C₂, 148, R₁, 142 and 144, shunting out the flow of current through contact C₁. Contact C₁ is a floating contact although other conventional contacting systems can be used, and as the outlet pumps begin to discharge liquid from the tank the floating liquid level sensing device will tend to move away thus breaking the electrical circuit. To compensate for this, the present circuit arrangement includes a holding circuit through contact C₂.

Simultaneously current flows through conductors 132, 134, 150, 152, 154, closed contact C₃, and conductor 156 to actuate pump means 114, thus discharging liquid from the vessel through proportioning conduits 122 and 124.

At the same time the cylinder 38 is in the unloading position, i.e. aperture 40 is 180° removed from the open bottom 76 of the hopper 74. Simultaneously with the flow of current to actuate the pump means 114, current flows through conductors 132, 134, 150, 152 and 158 to activate motor 80, the circuit being completed by the flow of current through conductor 160, time delay latch switch L₁, contact C₄ and conductors 156 and 144.

Time delay latch switch L₁ is positioned in its primary

position, as shown in full line in FIGURE 6, for a predetermined period of time, sufficient to permit rotation of the cylinder 38 through 180° from its unloading to loading position. At the end of this time latch switch L₁ is flipped to its secondary position, shown in dotted line, thus opening the circuit and de-energizing motor 80. The cylinder is then in its loading position to receive dry, particulate material from the hopper 74 through its open bottom 76.

When the water level in the tank is depressed to its lower level, contact C₅ closes. To insure that the current will flow through conductors 132 and 162, contact C₅ and conductor 164, relay R₂ and conductors 142 and 144, the resistance of relay R₁ must be greater than the resistance of relay R₂. With the flow of current through relay R₂, contacts C₆ and C₇ are closed. Current then flows through conductors 132, 162, 166, closed contact C₆, resistance B, relay R₂ and conductors 142 and 144, shunting out the flow of current through contact C₅. This latter holding circuit insures the continued actuation of pump means 86 since the floating contact C₅ will tend to open with the rising water level, thus shunting the flow of current through contact C₅. It should be noted, however, that the closing of contact C₆ should be slightly delayed to permit opening of contact C₂ thus preventing the current from flowing through the latter contact.

Simultaneous with the flow of current established through contact C₆ and relay R₂, current flows through conductors 132, 134, 150, closed contact C₇ and conductor 168 to energize pump means 86, thus delivering the liquid to the vessel 12 via the filter means 94. From filter means 94 the liquid flows through valve 100 operated by a solenoid which is in series with the pump means 86. The circuit is completed by the flow of current through conductors 142 and 144.

Also simultaneous with the flow of current through closed contact C₇ to energize pump means 86, current flows through conductors 132, 134, 150, 152, and 158 to energize motor 80, the circuit being completed by current flow through time delay latch switch L₁ (positioned in accordance with the dotted line of FIGURE 6), through conductor 160, electric flow switch 104 which closes on energization of pump means 86, and conductors 142 and 144. The time delay latch switch L₁ is positioned in its secondary position as shown in dotted line in FIGURE 6 for a predetermined period of time, sufficient to permit rotation of the cylinder 38 through 180° from its loading to unloading position. At the end of this time latch switch L₁ is flipped to its primary position, shown in full line, thus opening the circuit and de-energizing motor 80. The cylinder is then in its unloading position ready to be rotated in a second cycle.

When the water level again reaches its highest predetermined level contact C₁ closes and the cycle is repeated as above. It will be observed that because resistance B has been placed in the holding circuit for the filling portion of the first cycle and because the sum of the resistance of B and relay R₂ are greater than the resistance of relay R₁ current will flow through closed contact C₁ and relay R₁. The cessation of current flow through relay R₂ de-energizes the relay thus opening contacts C₅, C₆ and C₇, stopping the flow of liquid into the vessel 12. At the same time electric flow switch 104 is opened.

As a safety feature to prevent discharge of a liquid mixture from vessel 12 to a malfunctioning primary system there can be provided in the control system a relay which is connected to the pump means 114 to discontinue feeding the liquid mixture to the primary system via conduits 122 and 124. The control system can also be provided with a counter connected to the dispensing means to record the number of revolutions made by the cylinder 38 during a given period of time. Indicator lights can also be installed to show which part 75 of the device is activated and operating.

It will be understood from the above description that the operation of the novel device of this invention can be automatic and continuous or adaptable for batchwise operations. The device, for example, delivers a dry, particulate material to the interior of the vessel 12 only when a liquid is present therein, thus eliminating inadvertent damage to the equipment which could be occasioned by contact of the dry material therewith, especially when the dry, particulate material is reactive with the material from which the vessel is fabricated. The device also operates only when the primary system to which the liquid mixture is delivered, is functioning properly thus avoiding waste of the liquid mixture.

It will thus be seen that there has been provided by this invention a method and a structure in which the various objects hereinbefore set forth, together with many practical advantages, are successfully achieved. As various possible embodiments may be made of the mechanical and process features of the invention, all without departing from the scope thereof it is to be understood that all matter hereinbefore set forth or shown in the accompanying drawings is to be interpreted as illustrative, and not in a limiting sense.

What is claimed is:

1. Apparatus for dispensing and mixing a dry, particulate solid with a liquid comprising a hopper for storing said dry, particulate material, said hopper having an open bottom, a rotatable hollow cylinder mounted essentially exteriorly of said hopper and in communication with said hopper through the open bottom thereof, a mixing vessel in communication with said hopper through said cylinder, said cylinder provided with at least one longitudinally extending aperture in the peripheral wall thereof to allow ingress and egress of said dry, particulate solid from said hopper to said mixing vessel, a first pair of shroud members fixedly and spacedly positioned adjacent the open bottom of said hopper and said cylinder, said first pair of shroud members extending substantially parallel to the longitudinal axis of said cylinder, a second pair of shroud members fixedly and spacedly positioned adjacent the open bottom of said hopper and said cylinder, said second pair of shroud members extending substantially transverse to the longitudinal axis of said cylinder, said first and second pairs of shroud members being provided to retain said dry, particulate material in said cylinder when rotated to dispense said material in said vessel, means for delivering said liquid to said vessel, means for discharging a mixture of said solid and liquid from said vessel, liquid level sensing means for determining a predetermined low liquid level and a predetermined high liquid level in said vessel, electrical means operative in response to said low liquid level to deliver said liquid to said vessel, liquid flow sensing means positioned between said liquid delivering means and said vessel, means operative in response to said liquid flow sensing means to rotate said cylinder from a filling position to an intermediate dispensing position to dispense said solid material through the aperture in said cylinder into said mixing vessel, and electrical means operative in responsive to said high liquid level to discontinue the delivery of said liquid to said vessel, to rotate said cylinder from said intermediate dispensing position to said filling position and to discharge a mixture of said solid and liquid from said vessel to a liquid primary system.

2. Apparatus according to claim 1 including electrical means for discontinuing the discharge of said mixture to said liquid primary system when said primary system is non-operating.

3. Apparatus according to claim 1 including liquid filter means in fluid communication between said liquid delivery means and said vessel.

4. A process for delivering a mixture of a dry, particulate solid and a liquid to a liquid primary system from a mixing zone comprising the steps of sensing a low liquid level in said mixing zone, delivering a liquid to said mixing zone in response to said low liquid level sensed,

sensing the flow of said liquid to said mixing zone, dispensing a predetermined amount of dry, particulate solid to said mixing zone in response to said liquid flow sensed, continuing the flow of said liquid to a predetermined high liquid level while simultaneously, substantially homogeneously mixing said solid and liquid, sensing said high liquid level in said mixing zone, discontinuing the delivery of said liquid to said mixing zone and discharging said mixture to said liquid primary system in response to said high liquid level sensed.

5. The process according to claim 4 including filtering said liquid prior to delivery to said mixing zone.

6. Apparatus for dispensing and mixing a dry, particulate solid with a liquid comprising a hopper for storing said dry, particulate material, said hopper having an open bottom, a rotatable hollow cylinder mounted exteriorly of said hopper and in communication with said hopper through the open bottom thereof, a mixing vessel in communication with said hopper through said cylinder, said cylinder being provided with a plurality of apertures, axially and angularly spaced in a spiral-like arrangement in the peripheral wall thereof and with a disk between each successive aperture to define a plurality of separate compartments in said cylinder to allow ingress and egress of said dry, particulate solid from said hopper to said mixing vessel, at least one pair of shroud members fixedly and spacedly positioned adjacent the open bottom of said hopper and said cylinder for retaining said dry, particulate material in said cylinder when rotated to dispense said material in said vessel, means for delivering said liquid to said vessel, means for discharging a mixture of said solid and liquid from said vessel, sensing means for determining the liquid level in said vessel and electrical means operative in response to said liquid level to control the delivery of said liquid to said vessel, to rotate said dispensing means and to control the discharge of said mixture from said vessel.

7. Apparatus for dispensing and mixing a dry, particulate solid with a liquid comprising a source of said solid, an open top mixing vessel, means for delivering said liquid into said vessel, means for discharging a mixture of said solid and liquid from said vessel, liquid flow sensing means positioned between said vessel and said liquid delivering means, means responsive to said liquid flow sensing means to actuate means for dispensing a predetermined amount of said solid into said vessel, said solid dispensing means comprising a hollow rotatable closed end cylinder mounted above the open top of said mixing vessel and provided with a plurality of apertures axially and angularly spaced in spiral-like arrangement in the peripheral wall thereof and a disk midway between each successive aperture to define a plurality of separate compartments in said cylinder to allow ingress and egress of said dry, particulate material from said source of solid to said mixing vessel.

8. Apparatus for dispensing and mixing a dry, particulate solid with a liquid comprising means for storing said dry, particulate material, dispensing means in communication with said storing means, a mixing vessel in communication with said storing means through said dispensing means, means for delivering said liquid to said vessel, means for discharging a mixture of said solid and liquid from said vessel and control means for activating (a) said dispensing means, (b) said liquid delivering means and (c) said mixture discharge means, said control means including means for sensing the flow of liquid to said mixing vessel, means operative in response to the sensed liquid flow to activate said dispensing means, means for sensing the liquid level in said vessel and means operative in response to the sensed liquid level to actuate said liquid delivery means and said mixture discharge means.

9. The apparatus of claim 8, wherein said dispensing means comprises a rotatable hollow cylinder provided with at least one aperture in the peripheral wall thereof to allow ingress and egress of said dry, particulate solid from said storing means to said mixing vessel.

10. Apparatus for dispensing and mixing a dry, particulate solid with a liquid comprising a hopper for storing said dry, particulate material, said hopper having an open bottom, a rotatable hollow cylinder mounted essentially exteriorly of said hopper and in communication with said hopper through the open bottom thereof, a mixing vessel in communication with said hopper through said cylinder, said cylinder provided with at least one longitudinally extending aperture in the peripheral wall thereof to allow ingress and egress of said dry, particulate solid from said hopper to said mixing vessel, at least one pair of shroud members fixedly and spacedly positioned adjacent the open bottom of said hopper and said cylinder for retaining said dry, particulate material in said cylinder when rotated to dispense said material in said vessel, means for delivering said liquid to said vessel, means for discharging a mixture of said solid and liquid from said vessel and control means for actuating (a) said rotatable hollow cylinder, (b) said liquid delivery means and (c) said mixture discharge means, said control

5
means including means for sensing the flow of liquid to said mixing vessel, means operative in response to the sensed liquid flow to actuate said rotatable hollow cylinder from a loading to an unloading position, means for sensing the liquid level in said vessel and means operative in response to the sensed liquid level to actuate said liquid delivery means and said mixture discharge means.
